EDUCATIONAL TOY FRAME
Glen F. Benkelman, 1105 Homewood Drive,
Lakewood, Ohio
Filed May 25, 1959, Ser. No. 815,539
1 Claim. (Cl. 46—25)

This invention relates to toy blocks, and more particularly to toy building blocks suitable for interlocking to form various structures.

Children like to play with blocks and as a child grows older he very likely will have a propensity to enjoy building structures of his own design. This is both educational and enjoyable for the child. In his building, the child, in many cases, enjoys experimenting with and changing the structure he has created, but yet he may desire that these structures have a rather high degree of stability. He will also desire that the blocks he uses be capable of being assembled and disassembled with ease and simplicity.

Accordingly, one of the principal objects of this invention is to provide a toy building block which can be quickly combined with a similar block in forming a structure.

Another object of this invention is to provide a toy building block which can be used with similar blocks to build a relatively stable structure.

Another object of this invention is to provide a toy building block that is relatively simple to combine with similar blocks to provide a variety of structures.

Another object of this invention is to provide a toy building block that has means for operative connection to similar toy blocks.

A related object is to provide a toy building block that has end extensions that can be interlocked with similar toy blocks.

Another related object of this invention is to provide a toy building block that has an extension to be an operative connection with a similar block and means for holding a similar block in operative connection.

Another related object of this invention is to provide a toy building block having extensions, apertures to accept similar extensions, and angularly extending intersecting apertures to receive pins to lock similar blocks together.

Another related object of this invention is to provide an elongated square cross-sectioned building block having extensions and extension-accepting apertures, and angularly extending intersecting apertures in the blocks to lock the extensions to a similar block by means of a locking pin.

Other objects and a fuller understanding of the invention may be had by referring to the following description and claims, taken in conjunction with the accompanying drawings, in which:

FIGURE 1 is a perspective view of a group of building blocks in operative connection;

FIGURE 2 is a plan view of two building blocks;

FIGURE 2A illustrates an alternative embodiment permitting coupling and pinning from either top or side position;

FIGURE 3 is a side elevational view of the blocks of FIGURE 2;

FIGURE 3A is a side view of the female ended block of FIGURE 2A;

FIGURE 4 is an enlarged plan view of the block shown in FIGURE 2;

FIGURES 5 through 8 are each side elevational views of alternate embodiments of the invention;

FIGURE 9 is a plan view of a filler block;

FIGURE 10 is a side elevational view of the block shown in FIGURE 9; and,

FIGURE 11 is a side elevational view of a locking pin.

2

Referring to FIGURE 2 of the drawings, there is illustrated a pair of mated building blocks 10 and 30. Block 10 is a female structure and block 30 is a male structure. The blocks 10 and 30 have a body portion 11 having first and second spaced opposite ends. First and second female connector means are provided, each composed of two rectangular extensions 12 and 24. The body portion 11 of the blocks each has a face surface 13, 14, 15, and 16 defining, in the illustrated embodiment, a rectangular cross-sectional body. The extensions 12 and 24 are defined by the face surfaces 20 and 21 respectively, which are extensions of body surfaces 13 and 15, and by a connection means accepting slot 17. A locking pin aperture 23 extends transversely through the extensions 12 and 24 which are provided to accept a locking pin, such as locking pin 26 illustrated in FIGURE 11.

The body portion has a connection means receiving aperture 19 dimensioned and positioned to accept male connection means of another block and serve as a socket to receive such connection means. The width of the body 11 in the area of the socket 19 is such that the distance from one surface of socket 19 to the parallel face surface of the block will permit one of the connections 20 or 24 to reside in the socket 19 and the other extension to reside on the surface of the block, with the body structure therebetween residing in and meshing with the slot 17. The connections 20 and 24 each have approximately the dimensions of connector 12. Thus, another block dimensioned as the block 10 may be interlocked with the block 30 by inserting one of the extension members into the socket 19 and the other extension member positioned on the face surface of the block. An offset connection is thus provided.

A pin aperture 18 extends through the body 11 in a transverse direction to the direction of the socket 19 and is dimensioned to receive a pin 26. Thus, the mated blocks may be removably interlocked for a solid construction.

In the preferred embodiment as illustrated, the side walls of the extensions 20 and 24 are extensions of the surfaces 14 and 16. Thus, the block 10 is a longitudinal member of rectangular cross-section having slotted ends to receive a male connection or to receive one of the resultant extensions of the slotted female block and with cross apertures to receive locking pins.

Also in FIGURE 2, the male block 30 is constructed with all dimensions and proportions similar to the blocks 10, but with single extension members or male connections 12 as male connections. The connections 12 are dimensioned exactly as each of the extensions 20 and 24. Hence, it will be seen that the lateral dimension of the block 10 is three times the lateral dimension of a single extension 20 or 24, and that the lateral dimension of the extensions 12 and 24 is equal to the lateral dimension of the slot 17. This modular arrangement permits a multiplicity of combinations not heretofore available in conventional toy blocks.

The block 11 is also provided with transverse pin receiving openings indicated by reference character 23A, which are provided for the purpose of permitting the connections 12 to be locked into engagement with slots 17, socket 19, or a slot 19A provided through the central portion of the male blocks 30.

The versatility of this toy construction is greatly enhanced by the modification set forth in the FIGURES 2A and 3A. Here it will be seen that the socket areas centrally of the blocks are in the form of two cross slotted sockets 29 and 29A. Hence, the female extensions or the male extensions of other blocks may be inserted in either direction through the central portion and may be locked therein by a pin 26.

The FIGURE 4 illustrates the male version of the blocks set forth in FIGURE 2, for better comparison with the alternate structures of FIGURES 5 through 8.

In the FIGURE 5 the construction is identical in all respects with the block of FIGURE 4 with the exception that the male connection, indicated by reference character 35, is half the thickness of the similar extension 12 of FIGURE 4. It is often desirable to have two blocks extending in two directions from another block. Since the extension members of the block of FIGURE 2 are all dimensioned to fit exactly into the recessed sockets, such extensions from a single location in opposite directions is impossible. However, with the half thickness extension 35 the two blocks of FIGURE 5 may be inserted into any given socket recess and extended from that single recess in alignment or at an angular direction, in the case of an end junction. Furthermore, whenever such a block as that illustrated in FIGURE 5 is to be extended alone from a single socket, a filler block which can be considered a part of the male connection means 36 as set forth in FIGURE 9 may be inserted with the male connection 35 to fill the unused space intended for another connection 35. Locking pin apertures without reference characters are provided through the connection 35 and through the similar blocks set forth in FIGURE 9 for the same purpose as set forth previously.

The block illustrated in the FIGURE 6 has one female end and one male end, and provides further combination effects.

The block of FIGURE 7 is provided with a plurality of socket recesses through the body portion of the block and the illustrated embodiment sets forth two sockets passing through the body of a block in one direction and the third passing at a 90-degree angle through the opposite direction.

The FIGURE 7 illustrates a hybrid type of block with a female and a male end and the FIGURE 8 illustrates the same type of central body structure with two male ends.

Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

I claim:

A toy building block, comprising, a body of square cross section longer than wide, said body having at least one projection from each end which projection is one-third as thick as the block width and is as wide as the block, one slot through the body between two sides and another slot intersecting the one slot and extending between the remaining two faces, said slots dimensioned one-third as thick as the block and as wide as the block to receive an end projection of another block having end projections of like form, a pin aperture axially of each slot and centered with respect to the slot, each end projection having a transverse lock-pin opening, whereby a projection may be inserted into a slot of a like block and a pin placed to lock the projection into the block slot.
